UNITED STATES PATENT OFFICE.

JAMES FRANK DURYEA, OF SPRINGFIELD, MASSACHUSETTS, ASSIGNOR TO
THE UNITED POWER VEHICLE COMPANY, OF NEW YORK, N. Y.

THROTTLE-VALVE FOR STEAM-ENGINES.

SPECIFICATION forming part of Letters Patent No. 663,829, dated December 11, 1900.

Application filed March 7, 1900. Serial No. 7,662. (No model.)

To all whom it may concern:

Be it known that I, JAMES FRANK DURYEA, a citizen of the United States of America, and a resident of Springfield, in the county of 5 Hampden and State of Massachusetts, have invented certain new and useful Improvements in Throttle-Valves for Steam-Engines, of which the following is a full, clear, and exact description.

10 This invention relates to improvements in the controlling appliances which are manually operated for steam-engines.

The improved devices are more especially designed for utilization on steam-engines 15 which are employed for the propulsion of motor-vehicles or automobiles.

The invention in part relates to improved mechanism for operating the throttle-valve to open and to close the same as desired.

20 The invention also embodies, in conjunction with the throttle-valve and with a chamber or conduit adjacent the throttle-valve which leads from the steam-supply pipe to the steam-chest of the engine, a secondary or relief 25 valve opening to the escape of any steam which may leak past the throttle-valve when the latter is closed, whereby at the time the engine and vehicle is stopped and the relief-valve opened there can be no passage of steam

30 under pressure into the engine to cause any unexpected starting of the engine and movement of the carriage from the place at which it was left to become endangered or to endanger traffic.

35 The invention also embodies, in conjunction with the throttle-valve-operating devices, operating means for the relief-valve, so that when the throttle-valve is by a movement of its operating connection brought to its closed 40 position a still further movement of the same device which effects the closing of the throttle-valve will insure the opening of the relief-valve.

The invention also embodies the combination, 45 with the throttle-valve-actuating means, of the lever which is adapted for a swinging motion for effecting through suitable connections the shifting of the link-motion which controls the cut-off and reversal of the engine and the dog or catch which restrains the cut-off-controlling lever in any of its given set

positions, so that a proper movement of the rod or part forming one of the connections in the throttle-valve-operating device may without affecting the throttle-valve insure the release of the dog for its disengagement to permit said controlling-lever for the cut-off to have its appropriate swinging movement as desired.

The invention furthermore consists in details of arrangement and particular combinations and constructions of parts, all substantially as hereinafter fully described, and set forth in the claims.

Reference is to be had to the accompanying drawings, in which—

Figure 1 is a plan view of a portion of a motor-vehicle, indicating the engine and its boiler therewith connected and showing the improved manually-operated controlling devices which have been above mentioned. Fig. 2 is a side elevation of the same. Fig. 3 is a plan view, on a larger scale, more especially of the improved devices. Fig. 4 is an elevation of the same part shown in Fig. 2, but on a larger scale; and Fig. 5 is an elevation as taken at right angles to Fig. 4.

In the drawings, A represents a steam-engine of an ordinary type, to the steam-chest of which the pipe B conveys steam from the boiler C.

The engine and boiler in Figs. 1 and 2 are shown as mounted upon the body D of a motor-wagon.

E represents the usual link-motion for varying the cut-off and for stopping and reversing the engine, operating in the manner which is very common and well known.

a represents the throttle-valve, which closes against the valve-seat a^2 in the chambered casting or coupling-section F, which is between the steam-pipe sections 10 and 12. The said casting or coupling section F, which constitutes in substance an enlargement in the conduit for carrying the steam from the boiler to the engine, has the extension boss and gland 13 opposite the aforesaid valve-seat through which the stem d of the throttle-valve plays. The said chambered casting F also has a valve-seat opening e, connected with which is an outlet-passage e^2 , and provided to the valve-seat opening is the relief-valve f, opening inwardly

and having the stem f^2 , which extends parallel with the throttle-valve stem, its location being comparatively near that of said throttle-valve stem.

5 The throttle-valve stem has at an intermediate part of the portion thereof between the gland 13 and its outer end shoulder 14 the shoulder or abutment 15, outside of which engages the apertured end 16 of an elbow-lever g , which is pivotally mounted in the stationary bracket or fixture 17, secured on the body of the vehicle.

With the arm of the lever g which is angular to the arm or extremity 16 thereof which 15 embraces the throttle-valve stem, is connected the connecting-rod or thrust-rod h , which ranges horizontally at about right angles to the lengths of the parallel stems of the throttle and relief valves. A portion of the length 20 of the thrust-rod h is extended through and inclosed within the tubular rock-shaft m , which is mounted for rotational rocking movement in the brackets or fixtures 18 18 therefor, secured to the body of the vehicle. The 25 end of the said rod h which is the farther from the angular lever g has connection with the horizontal crank member i , which is provided and affixed to the lower end of the upstanding operating shaft rod or bar j , which is extended upwardly through and within the hollow lever G , which latter is the operating-lever for manually controlling the position of the cut-off link-motion E , it being here explained that the lower end portion of this 30 swinging lever G is affixed as a vertical angular extension thereof to the end portion of the tubular rock-shaft m , which has its location beyond or outside of the journal sleeve or bushing 19, and that the opposite end of the tubular rock-shaft m , which is shown as between the swinging lever G and the aforementioned angular lever g , has the cranked extension or lever-arm b , between which and the link-motion E is the link or connecting-rod b^2 .

40 45 The upper end of the swinging lever G is constructed with an arc-shaped or circular flange 20, which has therein notches 22.

n represents the part or handle of the device, which is directly grasped and by which 50 upon various manipulations thereof all of the devices may be operated. This horizontal handle has at its inner end the depending hub 24, within the socket of which is fitted and secured by the cross-pin 25 the upper end of the vertical rod j . The said handle n is axially bored on two diameters, through which plays the stem n^2 , the outer end of which is enlarged or shouldered, as seen at n^3 , while the opposite end has the catch-lug or dog n^4 , which is adapted to engage in either of the aforesaid notches 22.

55 60 65 n^5 represents a spiral spring inclosed within the tubular handle and operating to force the stem to the rightward as the parts are seen in Fig. 4, whereby the catch-lug or dog will engage with certainty in one of the notches 22

therefor and be retained in such engagement against accidental displacement.

As a matter of convenient design the upper end portion of the swinging lever G is formed 70 as a complete shoe to give a bearing for the turning movement therein at the upper end portion of the rod j , while the lower portion of this lever is formed of a cross-sectional **U** shape, with the web at 26, in which also is a 75 bearing-support for the lower end portion of said rod j . Said part 26 constitutes a stop for the upward drawing movement of the rod j for the purpose hereinafter explained. The lower end 27 of the tubular upper part of the 80 lever G constitutes a stop or abutment for the upper end of the spiral spring 28.

o^2 represents a sleeve-like shank of the dog o , which engages in the notches 30 of the sector-plate q , which is mounted on the body or 85 framing of the vehicle in a vertical plane coincident or parallel with the plane of swinging motion of part G . The said dog is loose about the rod j , so that the turning of the rod will not turn the dog, and yet any lifting motion of the rod will insure the lifting of the dog because of the cross-pin t thereunder.

To operate the mechanism to open or close the throttle-valve, the handle-arm n is grasped by the hand, the ball or back part of the hand exerting a crowding contact against the end portion n^3 of the stem, which crowds the latter endwise through the handle, carrying the catch-lug n^4 out of engagement with the notched flange of the swinging lever G , and 90 now the handle may be turned in a horizontal plane to partially rotate the vertical rod j and through the crank-arm i thereof and thrust-rod cause the swinging of the angular lever j to either force the throttle-valve through its 95 stem open or closed. It will be here pointed out that the angular lever g has opposite the arm 16 the second lever-arm 33, having a forcing action against the stem f^2 of the relief-valve. The relief-valve is shown as provided with a 100 spring f^3 for normally closing it. It will also be pointed out that the abutment or shoulder d^2 on the throttle-valve stem, against which the member 16 of the angular lever g bears, is 105 spring-supported on the stem and is thereby yielding in a direction toward the end of the stem against the compression of the spiral spring d^3 , interposed between the shoulder-collar d^2 and the stop 14. Now, assuming that the handle n is being swung around horizontally in 110 a direction to swing the lever g in the direction of the small arrow shown in Fig. 3, it will be understood that the part 16 after having forced the throttle-valve closed against its seat a^2 may on a continued swinging movement of 115 the handle n and of the lever g in the indicated direction have a lost motion relatively to the throttle-valve stem concurrent with which the opposite lever-arm 33 will force the relief-valve open, which may remain so open on 120 any occasions when the establishment of such condition is desired, more especially at a time

125 130 135

when the vehicle is left standing with steam on. With the relief-valve thus left open there can be no danger of steam being permitted to enter under pressure into the steam-chest of the engine, as might possibly occur in the event of the throttle-valve failing to fully close by reason of the lodgment of sediment in the valve-seat or of leakage of the valve. It will be perceived that a certain degree of swinging movement of the handle *n* in the proper direction to close the already-opened throttle-valve may be given to such handle without the additional movement sufficient to open the relief-valve. Now, again, by lifting the stem *j* through the handle *n* sufficiently far as to raise the dog *o* clear from the notched sector-plate the lever *G* is free to be swung in either direction to impart through the connection described between said lever and the link-motion *E* for the cut-off the changing of the cut-off as may be desired.

The mechanism is so constructed or designed that the elevating movement of the rod *j* to release the dog *o* from the sector-plate may be comparatively slight, and this movement need not be so great as to cause the lifting of the catch-lug entirely out from which ever of the notches 22 said lug may be in engagement with.

Having thus described my invention, what I claim, and desire to secure by Letters Patent, is—

1. In an engine, the combination with the steam-conduit having the throttle-valve, and in the portion of the steam-conduit between the throttle-valve and the engine, a relief-opening having a relief-valve normally closing the same, and means for operating it, whereby with the relief-valve open and the throttle-valve closed, any leakage of steam past the throttle-valve will be diverted from the engine.

2. In an engine, the combination with the steam-conduit therefor having a throttle-valve, and having in the portion of the steam-conduit between the throttle-valve and engine, a relief-opening having a relief-valve normally automatically closing said opening, operating means for the throttle-valve arranged in conjunction with the relief-valve to open the latter only after the throttle-valve has been closed, for the purpose set forth.

3. The combination with the engine and the steam-pipe thereof having the throttle-valve *a* and the extended stem and said conduit having between the throttle-valve and its connection with the engine, the relief-opening *e* having the relief-valve *f* and a valve-stem therefor, a lever *g*, opposite arms of which are arranged to engage both the stem of the throttle-valve and the stem of the relief-valve, for the conjoint operations of both said valves, for the purpose set forth.

4. The combination with the steam-conduit for the engine, having the valve-seat *a* and throttle-valve *a* provided with a stem *d* which

has the shoulder 15 and the yielding abutment *d*, and which conduit has between the throttle-valve in its connection with the engine the relief-opening *e* to which is provided the relief-valve *f* having a valve-stem and a closing-spring, of the lever *g* having the extensions or arms the one 16 engaging the throttle-valve stem between said parts 15 and *d* and the other 33 coöperating with the relief valve-stem, and means for imparting a swinging motion to said lever.

5. The combination with the throttle-valve stem *d*, of an angular lever adjacent the same and adapted to have an opening and closing engagement therewith, a vertical rod *j* mounted for a rotational movement and provided with a handle and with the crank portion *i*, and the connecting-rod *h* secured to said part *i* and the lever *g*, substantially as described.

6. The combination with the throttle-valve stem *d*, of an angular lever adjacent the same and adapted to have an opening and closing engagement therewith, a vertical rod *j* mounted for a rotational movement and provided with a handle, and with the crank portion *i*, and a part adjacent which said handle has its swinging movement provided with one or more catch-notches, a catch movably mounted on the handle to engage and disengage said notches, and the connecting-rod *h* secured to said part *i* and the lever *g*.

7. The combination with a throttle-valve, and with the link-motion for controlling the cut-off, of an engine, of a swing-lever connected with the link-motion, a rod bodily movable in conjunction with the swing-lever, and having an independent motion whereby to operate the throttle-valve.

8. In combination, the throttle-valve, and link-motion of the engine, a lever mounted for a swinging motion and connected with the link-motion, a confining-dog for the lever, and a part with which the dog may have engagement and disengagement, a rod bodily movable in unison with the lever and having an independent movement for operating the throttle-valve; and having a movement also independent of the movement of the lever for releasing the confining-dog for said lever to permit the latter to be swung.

9. In combination, the throttle-valve, and the link-motion for the cut-off, of the engine, of a swinging lever connected with the link-motion, a rod mounted to have its bodily movements in unison with said lever, and having a rotational movement, and an axial movement independently of said lever, crank-lever and link connections between the rod and the throttle-valve actuated by the rotational movements of the rod to open and close the valve, the confining-dog for the swinging lever, with which the rod, in its axial movement engages, for its release, to permit the lever to be swung.

10. The combination with the link-motion of an engine and the tubular rock-shaft hav-

- ing lever-and-rod connection with the link-motion, and said shaft having the affixed lever G, of the thrust-rod h, for operating a valve of the engine, extending through the tubular rock-shaft, a rod mounted to be swung bodily in unison with said lever G and to turn relatively thereto, provided with an operating-handle, and having a crank-arm connected with said thrust-rod.
- 10 11. The combination with the throttle-valve-actuating means, of the lever which is adapted for a swinging motion for effecting through suitable connections, the shifting of the link-motion which controls the cut-off and reversal 15 of the engine, and the dog or catch which restrains the cut-off-controlling lever in any of its given set positions, so that a proper movement of the rod or part forming one of the connections in the throttle-valve-operating 20 device may without affecting the throttle-valve, insure the release of the dog for its disengagement to permit said controlling-lever for the cut-off to have its appropriate swinging movement as desired.
- 25 12. In combination the link-motion, and le-

ver G, the notched sector-plate, the dog o engaged with the lever, and movable endwise relatively thereto, and adapted to engage and disengage the sector-plate, the tubular rock-shaft m, on which said lever is affixed and 30 from which it is angularly extended, having an arm connected with the link-motion, the thrust-rod h comprised in a valve-actuating mechanism, extended through the tubular shaft, the rod j located within or alongside 35 the lever G, and rotatably and axially movable relatively thereto, and having a crank-arm connection at one end with rod h, and having an operating-handle n at its other end, said rod having a shoulder or abutment, by 40 which, in its axial movement, the dog is engaged and released, all substantially as and for the purposes set forth.

Signed by me at Springfield, Massachusetts, this 5th day of March, 1900.

J. FRANK DURYEA.
